UNITED STATES PATENT OFFICE.

WILLIAM K. TWOMEY, OF CHICAGO, ILLINOIS.

GAS-BURNER.

1,199,130.

Specification of Letters Patent. Patented Sept. 26, 1916.

Application filed August 9, 1915. Serial No. 44,406.

To all whom it may concern:

Be it known that I, WILLIAM K. TWOMEY, a citizen of the United States, residing at Chicago, in the county of Cook and State 5 of Illinois, have invented certain new and useful Improvements in Gas-Burners, of which the following is a specification.

This invention pertains to gas burners in general but concerns more particularly features of novelty and advantage in devices 10 of this character resulting in a better intermixture of the ingredients of the gaseous mixture employed whereby to obtain a more complete combustion.

15 The main feature of this invention is the construction of the burners in such a way as to produce or augment the pulsations or throbings in the pressure of the mixture and in the flames to secure a more efficient 20 commingling of the constituents of the mixture before burning and a more intimate mixture of the products of partial combustion. The flames burning at the jets or apertures of the burner are preferably so 25 located or positioned that their heated or incandescent gases will impinge on or become intermingled with those of one another, in this way so mixing the gaseous elements that a better and more complete 30 combustion will occur. In some instances it is desirable that these flames play against or bombard a wall to effect the same general result. In the preferred embodiment of the invention the burner is so shaped or constructed 35 that the gaseous mixture entering it strikes against an abutment or deflector, breaking up the main general current into parts of somewhat differing pressures, resulting in fluctuations in the pressures at 40 the jets and variations in the flames. In order to still further disturb or unequalize the pressure conditions in the burner it is conveniently provided with supplemental or secondary jets or perforations at which 45 throbbery or palpitating flames burn. In a word, one of the leading or prime objects of the invention is to produce tremulous, wavering, beating flames and variable pressure conditions, to improve the combustion 50 of the associated gaseous elements of the mixture.

A desirable embodiment of the invention is illustrated in the accompanying drawings forming a part of this specification and 55 throughout the various views of which like

reference characters designate the same parts.

In these drawings—Figure 1 is a vertical cross-section of a burner incorporating this invention; Fig. 2 is a plan view of the 60 burner proper; Fig. 3 is a central vertical cross-section through the same.

In this appliance the inlet pipe 9, of which only a fragment is shown, has the hollow burner attached to its upper end, such 65 burner comprising a suitably-shaped sheet-metal base or bottom 10 for a depending circular flange 11, adapted to receive the feed pipe, and having a marginal, upstanding, shallow flange 12. In this shell the sheet- 70 metal top 13 fits, the latter having a circular edge flange 14, snugly received in the correspondingly-shaped flange 12. Above flange 12 this wall 14 has a row of a relatively large number of equal spaced jet openings or 75 main burner apertures 15, at which the issuing gaseous mixture burns. Above these openings the wall 16 of the burner has a general conical formation, its center being pressed downwardly or deformed to provide 80 a deflector 17 of inverted cone shape concentric with the burner and the inlet pipe 9. Such conical deflector has a ring of supplemental or auxiliary openings or jets 18, at 85 which additional or complementary fluttering or quivering flames burn, these assisting in producing the pumping or throbbing of the gases and flames at the main jets 15. This burner of itself, and without the additional parts described below, may be successfully and satisfactorily employed for securing 90 an efficient combustion of the gaseous mixture. It operates substantially as follows: The incoming fluid mixture, for instance gas and air, through the pipe or tube 95 9 is of practically uniform pressure. As this stream of gas strikes the under surface of the inverted-cone deflector 17 it is broken up into currents or parts of different pressures, due to the conflict and interaction between such parts. This action may be likened to the playing of a stream of water from a hose against a wall. Such stream is 100 broken up into parts which spatter in all directions and are splashed to different distances because of the widely different forces acting upon them. During such scattering or spattering of the water its various parts strike one another, react and rebound, and cause a considerably disturbed and agitated 105 110

condition of the water as a whole. In somewhat similar manner the gaseous mixture is acted upon in impinging upon the deflector. Then these various currents of gas pass upwardly along the inner face of the deflector, some of them issuing through the jets 18, at which they burn in an unsteady and variable manner. The discharge of such portions of the gas at these apertures relieves the pressures somewhat at these points, while the pressures between the apertures are not thus modified or altered. This results in a still further unsettling or disturbance of pressure conditions in the burner. Then these bodies or portions of the gas, which are under different conditions as regards their pressures, pass downwardly along the under face of the cone-portion 16 and issue in downwardly directed streams or jets from the apertures 15 at which they burn. Their combustion creates upwardly acting air currents around and adjacent to the flames which neutralize or overcome their downward pressures so that the flames stand out substantially horizontally, at least adjacent to the burner. As has been explained, due to the fluctuating pressures, these flames pump or pulsate, and this action is taken advantage of in the individual burning flames to secure a better commingling of the gaseous ingredients of the mixture and a more thorough or complete combustion. It should be noted also that the flames spread as they extend away from the burner and that they impinge upon and become intermixed with one another. This throbbing or beating action of the flames and their gases creates a better intermixture of the gases when they impinge upon or mix with those of the next jet, in this way securing a more complete combustion because of such better mixing. Stated in another way, the pulsations, the collisions of the flames and gases and their intermixing, all combine to produce a more complete and effective combustion. Sometimes it is desirable, in order to produce this complete commingling of the gases, to let the flames play upon a wall to cause a greater disturbance and intermixture of the gases, and in some cases it is even desirable to employ a second combustion to complete the partial combustion carried on by such burner.

In Fig. 1 I have shown such an appliance. The burner is of the same construction as that described above and is incased within a shell or box comprising a base 19, having an aperture 20 for the admission of air from the bottom and for the accommodation of the pipe or tube 9. It also has a circular wall 21 disposed concentric to the burner proper and of such size that the currents of gas and flames will strike against its inner face. On lugs 22, rising from the top edge 65 of the shell 21 I provide a top or cover

plate 23, leaving space beneath the same in the edge of the wall 21. In the operation of this structure the combustion at the burner takes place as described above, but its flames and gases strike the wall 21 and become more thoroughly intermixed, sufficiently so that the products of partial combustion are now capable of further burning, and such secondary combustion occurs just beneath the plate 23 at the top edge of the wall 21. It will be understood that by thus remixing and commingling the heated products of partial combustion they may be again burned to effect a more complete combustion. It will also be appreciated that the pulsating action of the flames on the wall facilitates such further intermingling and mixing of the gases.

While I have presented herein two embodiments of the invention, which have been illustrated in detail and described more or less minutely, it is to be understood that the invention is not limited to the precise and exact structure and features of these devices, because many minor mechanical changes may be made therein without departing from the essence of the invention and without sacrificing any of its real benefits and advantages. The burners as shown and described are presented merely as illustrations of desirable ways of embodying the invention in practicable form and should not be considered in a restrictive sense.

I claim:

1. In an appliance of the character designated the combination of a gas burner having apertures through which the gaseous mixture escapes and at which the mixture burns, and having means to direct downwardly the jets of gaseous mixture issuing from said apertures, and an abutment wall across the path of the flames and against which the flames of said apertures play, substantially as described.

2. A gas burner having an inlet for the gaseous mixture, main burner apertures through which the gaseous mixture escapes and at which the mixture burns, and means to cause a pulsation of the flames burning at such apertures, substantially as described.

3. In an appliance of the character designated a gas burner having an inlet for the gaseous mixture, main burner apertures through which the gaseous mixture escapes and at which the mixture burns, and means to cause a pulsation of the flames burning at such apertures in combination with an abutment wall against which such pulsating flames impinge, substantially as described.

4. A gas burner having an inlet for the gaseous mixture and main burner apertures through which the mixture escapes and at which the mixture burns, and means in the path of the incoming mixture against which such mixture strikes and adapted to cause 130

pulsations in the flames burning at such apertures, substantially as described.

5. In an appliance of the character designated a gas burner having an inlet for the gaseous mixture and one or more main burner apertures through which the mixture escapes and at which the mixture burns, and means in the path of the incoming mixture against which such mixture strikes and 10 adapted to cause pulsations in the pressure of the mixture at such aperture or apertures in combination with an abutment wall against which the flame or flames of said aperture or apertures impinge, substantially 15 as described.

6. A gas burner having an inlet for the gaseous mixture and main burner apertures through which the mixture escapes and at which it burns, and one or more supplemental perforations at which a portion of the mixture escapes and burns and located to cause pulsations of the flames at said main apertures, substantially as described.

7. In an appliance of the character designated a gas burner having an inlet for the gaseous mixture and main burner apertures through which the mixture escapes and at which it burns, and one or more supplemental perforations at which a portion of the mixture escapes and burns and located to cause pulsations of the flames at said main apertures, in combination with an abutment wall against which said main flames impinge, substantially as described.

35 8. A gas burner having an inlet for the gaseous mixture, one or more main apertures through which the mixture escapes and at which it burns, means in the path of the incoming mixture against which the mixture strikes and adapted to cause pulsations in the flames burning in such aperture or apertures, and one or more supplemental perforations at which a portion of the mixture escapes and burns and located to augment 40 the pulsations of said main flames, substantially as described.

9. In an appliance of the character designated, a gas burner having an inlet for the gaseous mixture, a plurality of apertures 50 through which the mixture escapes and at which it burns, means in the path of the incoming mixture against which such mixture strikes and adapted to cause pulsations in the flames burning at such apertures, and 55 one or more supplemental perforations in

the burner at which a portion of the mixture escapes and burns and located to augment the pulsations of said main flames, and an abutment wall against which said pulsating main flames impinge, substantially as described.

10. A hollow gas burner having an inlet for the gaseous mixture, one or more main burner apertures at the outer portion of the burner, and a depression in the wall of the 65 burner in the path of the incoming mixture against which such mixture strikes, causing pulsations in the flames of said apertures, said apertures being a substantial distance below the top of said depression, 70 whereby the gaseous mixture in passing from the inlet to said apertures makes a general reversal in its direction of flow, substantially as described.

11. A substantially round, hollow gas 75 burner having an inlet for the gaseous mixture, one or more main burner apertures at the outer portion of the burner and a substantially inverted cone shaped depression in the wall of the burner in the path of 80 the incoming mixture against which such incoming mixture strikes, causing pulsations in the flames at said apertures, said apertures being a substantial distance below the base of said depression, substantially as described.

12. A hollow gas burner having an inlet for the gaseous mixture, one or more apertures at the outer portion of the burner, a depression in the wall of the burner in the 90 path of the incoming mixture against which such entering mixture strikes, causing pulsations in the flames at said apertures, and secondary apertures near the top of said depression at which secondary flames burn, 95 augmenting the pulsations of said main flames, substantially as described.

13. A hollow gas burner of general conical form having an inlet at the bottom and opposite said inlet a depression in the burner 100 top-wall of general inverted conical shape against which the incoming gaseous mixture impinges, and main burner apertures in the side-wall of the burner a substantial distance below the top or base of said depression, whereby to secure a general reversal of 105 direction of flow of the mixture through the burner and a pulsation of the flames at said apertures, substantially as described.

WILLIAM K. TWOMEY.
